(57) **CLAIM**

The ornamental design for a display screen or portion thereof with graphical user interface, as shown and described.

DESCRIPTION

The FIGURE is a front view of a display screen or portion thereof with graphical user interface showing the new design.

All the broken lines in the FIGURE illustrate a display screen or portion thereof with graphical user interface and form no part of the claimed design. The broken lines illustrating a communication device shown in the FIGURE illustrate a display screen or portion thereof with graphical user interface and form no part of the claimed design.

1 Claim, 1 Drawing Sheet
